UNITED STATES PATENT OFFICE.

EARL PLEMMONS, OF ASHBURN, GEORGIA.

AIR-MOTOR.

1,336,315.

Specification of Letters Patent.

Patented Apr. 6, 1920.

Application filed July 21, 1919. Serial No. 312,201.

To all whom it may concern:

Be it known that I, EARL PLEMMONS, a citizen of the United States, residing at Ashburn, in the county of Turner and State 5 of Georgia, have invented new and useful Improvements in Air-Motors, of which the following is a specification.

This invention relates to improvements in wind mills or air motors, and the principal 10 object of the invention is to provide a rotatable member provided with movable vanes which will automatically assume a position to be acted upon by the wind when they are moving with the wind and to assume a position 15 parallel with the air currents when they are moving against the wind.

Another object of the invention is to provide governor means for holding the vanes in partly open position, when moving with 20 the wind, when the speed of the wheel reaches a predetermined point.

The invention also consists in certain other features of construction and in the combination and arrangement of the several 25 parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of the invention placed 35 on a tower;

Fig. 2 is an elevation of one of the wings of the wheel;

Fig. 3 is a top view of the wheel;

Fig. 4 is a cross section through the wheel;

Fig. 5 is a detail view of the governor means.

In these views 1 indicates the tower for supporting the wheel at a suitable distance above the ground. This tower is composed 45 of the upright pieces connected together by the cross pieces and the inclined brace pieces as shown. Within the tower is journaled the shaft 2 which extends the full length of the tower. The wheel 3 is connected to the upper end of the shaft and this wheel consists of the hubs 4 suitably connected to the shaft and the arms 5, radiating from the hubs and carrying the vanes 6. As shown, 50 each pair of arms is provided with a plurality of vanes and each vane is carried by a rod 7 which has its ends pivotally mounted

in the arms of each pair. The vanes are so arranged that the outer edge of one vane will overlap the inner edge of the other vane so as to present a flat surface to the 60 wind. As will be seen from Fig. 4, when the vanes are moving with the wind they will be closed so as to offer the maximum resistance to the wind and thus cause the wheel to turn, but when the vanes are moving 65 against the wind they will be swung on their pivots so as to assume a position parallel with the wind and thus offer the minimum resistance to the movement of the wheel. In this way the wheel will be rotated by the 70 wind with the vanes assuming their closed position when moving with the wind and opening when moving against the wind. In order to prevent the wheel from rotating too fast, I provide governor means which 75 consist of a pair of disks 9 and a rod 8 for each vane. One disk of each pair is at the upper end of the wheel and the other disk is at the lower end thereof and said disks having secured thereto the ends of the rod, 80 said rod being located adjacent the edges of the disk. The disks on each arm are connected together by a rod 10 which has its inner end connected with a part of the hub by a spring 11 and its outer end is weighted 85 as at 12. Thus when the wheel is rotating at great speed the rods 10 will be moved outwardly by centrifugal force and thus rotate the disks and move the rods 8 into the paths of the vanes so as to prevent the vanes 90 from closing and thus leaving spaces between the vanes for the passage of the air. In this way the wheel is prevented from being rotated too rapidly.

Power may be transmitted from the shaft 95 2 in any desired manner, but as shown, I provide a cross shaft 13 which is suitably supported in the tower and which is connected with the shaft 2 by the gear wheels 14. This shaft is provided with a pulley 15 100 100 which is adapted to receive a belt which leads to the part to be driven. A cross bearing 16 is provided for the lower end of the shaft 2.

My device does not require any means for 105 holding it into the wind, such as windmills now made require, as my motor will continue to operate no matter in which direction the wind is from.

My device will also operate as a water 110 wheel with but few changes thereto.

It is thought from the foregoing descrip-

tion that the advantages and novel features of my invention will be readily apparent.

I desire it to be understood that I may make changes in the construction and in 5 the combination and arrangement of the several parts, provided that such changes fall within the scope of the appended claim.

What I claim is:—

A device of the class described comprising

a shaft, hubs carried thereby, arms radiating 10 from the hubs, vanes pivotally mounted in the arms, disks journaled in the arms, rods carried by the disks for engaging the vanes, a weighted bar connected with the disks on each arm and a spring connecting each of 15 said weighted rods to the hub.

In testimony whereof I affix my signature.
EARL PLEMMONS.
